UNITED STATES PATENT OFFICE.

WILLIAM S. NOYES, OF CHICAGO, ILLINOIS.

DESIGN FOR A SPROCKET-WHEEL AND CHAIN GUARD.

SPECIFICATION forming part of Design No. 27,069, dated May 18, 1897.

Application filed March 9, 1897. Serial No. 626,685. Term of patent 3½ years.

To all whom it may concern:

Be it known that I, WILLIAM S. NOYES, a citizen of the United States, and a resident of Chicago, in the county of Cook and State of Illinois, have invented and produced a new and original Design for Sprocket-Wheel and Chain Guards or Shields for Bicycles, of which the following is a specification.

In the accompanying drawings, Figure 1 is a perspective view of a guard embodying my design. Fig. 2 is a transverse section thereof.

The leading feature of my design consists in a plain or smooth exterior surfaced flanged margin and skeleton connecting web for a chain and sprocket guard for safety-bicycles.

A guard or shield of my design consists of a marginal frame A, the edges of which are continuous and unbroken or smooth, said margin having a flange A', which projects laterally therefrom in a direction, when applied to a bicycle, to cover the driving-chain thereof.

A guard or shield embodying my design is provided at its forward end with a circular web A², the rear side of which is connected with the marginal frame A by webs or braces a.

As herein shown, the outline a², defined by dot and dash, indicates the location of an ornamental bead following the circular contour of the web A², and the dotted sectors a³ indicate the position of openings through said web. I regard the modifications so indicated as merely colorable and intend this application to cover any such changes as are evident and unimportant or subsidiary to the design ³⁰ *per se*, and not liable to mislead or confuse. ³⁵

I claim—

The design for a sprocket-wheel and driving-chain guard or shield for bicycles, substantially as herein shown and described.

In testimony that I claim the foregoing as ⁴⁰ my invention I hereunto set my hand, this 3d day of March, 1897, in the presence of two witnesses.

WILLIAM S. NOYES.
